UNITED STATES PATENT OFFICE.

ARCHIE McDougall, of Salt Lake City, Utah Territory.

TRICYCLE.

SPECIFICATION forming part of Letters Patent No. 477,140, dated June 14, 1892.

Application filed September 21, 1891. Serial No. 406,370. (No model.)

To all whom it may concern:

Be it known that I, ARCHIE McDougall, of Salt Lake City, in the county of Salt Lake and Territory of Utah, have invented a new 5 and Improved Tricycle, of which the following is a full, clear, and exact description.

My invention relates to improvements in tricycles; and the object of my invention is to produce a simple, practical, and durable 10 machine, which is constructed in such a way that the driver may utilize both his hands and feet to propel it, and which consequently may be driven with great speed.

A further object of my invention is to provide 15 a convenient and effective means of steering the machine.

To this end my invention consists in certain features of construction and combinations of parts, which will be hereinafter described and claimed.

Reference is to be had to the accompanying drawings, forming a part of this specification, in which similar figures of reference indicate corresponding parts in all the views.

25 Figure 1 is a sectional side elevation of the machine. Fig. 2 is a sectional plan of the same. Fig. 3 is a broken detail section on the line 3-3 in Fig. 2, and Fig. 4 is a detail view of the axle-ratchet.

30 The machine is provided with two main driving-wheels 10, which are placed side by side in the usual manner and which are mounted on a driving-axle 11, one wheel being made fast to the axle and the other being 35 connected by a common form of ratchet mechanism to facilitate the easy turning of the machine, which ratchet mechanism consists of an inclosing case 12, secured to the wheel-hub, a ratchet-wheel 13, secured to the axle, 40 and arranged within the case, and pawls 14, pivoted in the case and arranged to engage the ratchet-wheel. The axle has mounted centrally thereon a frame 15, having depending end portions 16, which serve as hangers

45 to support the shaft of the driving sprocket-wheel 17, which sprocket-wheel is arranged directly beneath the driving-axle and connects by means of a chain 18 with the sprocket-wheel 19, which is secured to the axle. A 50 reach-rod 20 extends forward from the frame 15 and is supported on the steering-fork 21, in which the front wheel 22 is mounted in the

usual way. The reach-rod 20 has a frame 23 formed centrally thereon, and in the ends of this frame are mounted the shafts 24 of a 55 frame 25, which frame is of a rectangular shape and is held to oscillate in the frame 23, as shown in Fig. 3, and this frame 25 forms a support for a lever 26, which has a socketed head 27 and extends downward and slightly 60 rearward, being pivoted at its lower end, as shown at 28, to a connecting-rod 29, which extends rearward and has its rear end pivoted to the crank 30 of the driving sprocket-wheel 17. The outer ends of the shaft 24 terminate 65 in depending parallel cranks 31, which are curved rearward and have pedals 32 at their lower ends. The socket 27 in the head of the lever 26 forms a support for the lower end of the handle-bar 33, which extends upward 70 through the upper portion of the frame 25 and terminates at the top in a convenient handle 34, the handle-bar being arranged so that it will be within easy reach of the tricycle-seat. The handle-bar 33 carries near its lower 75 end a sprocket-wheel 35, which is held to turn in the open middle portion of the frame 25 and which connects by a chain 36 with a sprocket-wheel 37, which is secured to the top of the steering-fork, and it will thus be seen 80 that by twisting the handle-bar the sprocket-wheel 35 will be twisted and the steering-fork turned so as to properly guide the machine. The handle-bar is intended to be moved backward and forward, too, in propelling the machine; but it will be understood that the 85 sprocket-wheel 35 is arranged at the center of the motion, so that it will not have a reciprocating motion worth mentioning.

The machine is provided with a seat 38, 90 which may be of any approved construction and which is mounted on the spring-tongue 39, the tongue being curved, so as to extend through a lug 40 on the frame 15, and it may be held in place by a cam-lever 41, adapted 95 to turn so as to impinge on the tongue, or any other suitable mechanism may be substituted for the lever. The seat, however, should be adjustable backward and forward, so as to bring the rider in the proper position in relation to the handle-bar and the driving-pedals. 100

The operation of the machine is as follows: The rider places his feet on the pedals 32 and with his hands grasps the handle 34 of

the handle-bar, and then pushes back and forth alternately with his feet and hands, and this movement causes the frame 25 to oscillate, and an oscillating movement is imparted 5 to the lever 26, and the motion is transmitted by means of the connecting-rod 29 and crank 30 to the driving sprocket-wheel 17 and thence to the axle, the connecting-rod and crank serving also to convert the oscillating into a 10 reciprocating motion. To steer the machine, the rider simply twists the handle-bar, which operates on the steering-fork in the manner already described.

Having thus described my invention, I 15 claim as new and desire to secure by Letters Patent—

1. A tricycle comprising the usual driving and steering wheels, a driving-axle connected in the driving-wheels, a frame mounted centrally on the axle and connected by a reach with the fork of the steering-wheel, a driving sprocket-wheel mounted beneath the axle and having a sprocket-wheel and chain connection therewith, an oscillating lever mounted on the 25 reach, and an operative connection between the lever and driving sprocket-wheel, substantially as described.

2. A tricycle comprising parallel driving-wheels connected by a driving-axle, a steering-wheel arranged in advance of the main 30 wheels and connected by a reach with a frame on the driving-axle, a sprocket-wheel pivoted on the axle-frame and connected by a chain with a sprocket-wheel on the axle, a seat 35 mounted on the axle-frame, an oscillating and revolute lever pivoted on the reach and connected by a rod and crank with the driving sprocket-wheel, and a sprocket-wheel and

chain connection between the oscillating lever and the steering-fork, substantially as de- 40 scribed.

3. The combination, with the tricycle wheels and axle, the frame mounted on the axle, and the sprocket-wheel mechanism for driving the axle, of a reach extending from the axle-frame to the fork of the steering-wheel, a frame pivoted on the reach and provided with a depending lever, a rod-and-crank connection between the lever and the driving sprocket-wheel, a pedal mechanism for oscillating 50 the pivoted frame, a handle-bar mounted in the pivoted frame and held to turn therein, and a sprocket-wheel and chain connection between the handle-bar and the steering-fork, substantially as described.

4. The combination, with the driving-axle, the frame mounted thereon, and the sprocket-wheel mechanism for driving the axle, of a reach extending from the axle-frame to the steering-fork, said reach having a horizontal frame formed centrally thereon, an oscillating frame pivoted in the reach-frame and having a depending lever connected by a rod and crank with the driving sprocket-wheel, depending parallel cranks connected with the 60 oscillating frame and carrying pedals at their lower ends, a handle-bar mounted in the oscillating frame and held to turn therein, and a sprocket-wheel and chain connection between the handle-bar and the steering-fork, 70 substantially as described.

ARCHIE McDougall.
